UNITED STATES PATENT OFFICE

CHARLES E. DAVIS, OF CHICAGO, ILLINOIS, ASSIGNOR TO GOODMAN MANUFACTURING COMPANY, OF CHICAGO, ILLINOIS, A CORPORATION OF ILLINOIS

MINING MACHINE

Application filed October 30, 1922, Serial No. 597,722. Renewed May 2, 1929.

This invention relates to improvements in mining machines and has for its principal object to provide a new and improved device of this description, which is capable 5 of being quickly and easily handled during its operation and during its movement from place to place.

More specifically, the object of the present invention is to provide an improved 10 construction of a machine of the type shown and described in a prior application bearing Serial No. 444,767, filed February 14, 1921. This type of machine has a main frame, preferably mounted upon wheels, a 15 cutting element separate from this main frame and a controlling connection arranged so that it can lift and lower the cutting element and the device may further be arranged so that the controlling connection does 20 not support the machine while the machine is cutting, the cutting element being supported upon the floor of the mine and being free to follow any unevenness of the floor, 25 said cutting element during the cutting movement, independent of any vertically acting support. This controlling connection may thus be used to lift the cutting element and carry it to the point of use and lower it to the floor and then the lifting 30 action may cease and the cutting element be supported on the floor, thus giving it great freedom of movement so that it may cut around stones and other hard obstacles instead of cutting through them and may 35 follow the floor of the mine whatever its form, shape, contour or arrangement may be. A machine of the type described permits the cutting element separate from a main frame or truck to be handled as 40 though it were on the truck and yet makes it unnecessary to unload it from the truck when being operated or load it on the truck when being carried from point to point.

In the mining machine disclosed in my 45 prior application above referred to, the controlling connection between the main frame and the cutting element includes a pair of controlling arms having their rear ends pivotally connected to the main frame at opposite sides thereof and diverging there-

from to pivotal connections on opposite sides of the cutting element. This construction provides a modified pantograph movement adapted to control the angular positions of the cutter arm with respect to the main frame in a peculiar manner particularly adapted for use in cutting relatively narrow entries. In the present invention, means are further provided for shifting the position of these controlling arms whereby under certain conditions, as for instance when cutting relatively wide rooms, this pantograph movement may be dispensed with and the controlling arms will maintain the cutter arm in a radial position with respect to the axis of the controlling connection. Other features of improvement will appear in the following specification from time to time as the description proceeds.

I have illustrated one form of my invention wherein—

Figure 1 is a plan view of the machine with the cutter bar at the forward end removed.

Fig. 2 is a side elevation of the machine 73 shown in Figure 1.

Figure 3 is a side view of a portion of the machine illustrating the mechanism for raising and lowering the cutting element.

Figure 4 is a sectional view taken on line 4—4 of Figure 2.

Figure 4^a is a fragmentary plan view showing how the anchor plate may be locked to the moving frame.

Figure 5 is a sectional view taken on line 5—5 of Figure 1, but drawn on a somewhat larger scale than Figure 4.

Figure 6 is a sectional view taken on line 6—6 of Figure 1.

Figures 7 and 8 are details of the eccentric mechanism for adjusting the angular position of the cutter bar with relation to the floor.

Figure 9 is a sectional view taken on line 9—9 of Figure 6.

Figure 10 is a sectional view taken on line 10—10 of Figure 6.

Figure 11 is a sectional view taken on line 11—11 of Figure 1.

Figure 12 is a sectional view taken on line 12-12 of Figure 1.

Figure 13 is a sectional view taken on line 13-13 of Figure 1.

Figure 14 is a sectional view taken on line 14-14 of Figure 1.

Figure 15 is a diagrammatic view showing the arrangement of the controlling arms in one position while making a sumping cut in a narrow room or entry.

Figure 16 is a diagrammatic view showing the machine after the lateral cut has been made with the parts in position to make the final cut.

Figure 17 is a diagrammatic view of the machine making a slabbing cut along one side of the track.

Figure 18 is a diagrammatic view showing the arrangement of the controlling arms 20 preparatory to making a sumping cut in a wide room.

Figure 19 is a view similar to Figure 16, but with the machine in position after the sumping cut has been completed and positioned to make a lateral swinging cut.

In carrying out my invention, I provide a machine having a main frame 1 mounted upon wheels 2. A movable frame 3 is supported on the main frame 1 and arranged 30 for pivotal swinging movement about a hub 4 which fits in a projection 5 on the frame 3 as best shown in Figure 5. The cutting element indicated at 10 is movably supported with respect to the main body of the machine by means of a pair of supporting arms 11, 11 (see Figs. 1, 2 and 3) arranged so that the cutting element may be moved vertically into various positions. The supporting arms are connected at opposite ends to a transverse rock shaft 12 pivotally mounted 40 between supports 13, 13 carried on the moving frame 3. A rearwardly extending rocking arm 14 is connected to one end of the shaft 12.

The rocking arm 14 may be actuated by any suitable mechanism to raise or lower the supporting arms 11, 11 and the cutting element carried thereby. In the present instance, this mechanism includes a gear segment 15 on the end of arm 14 which cooperates with a gear segment 16 mounted on a bearing 17. A rock arm 18 is operatively connected to move with the gear segment 16 and is adapted to be rocked by a link 19 eccentrically connected to a rotating gear 20, as best shown in Figures 2 and 3. Said link is provided with a slot 21 in which a pin 22 on the gear 20 is engaged. The gear 20 may be rotated in any suitable manner, as for instance, by means of a spur gear 23 and worm gear 24 having operative connection with a worm 25. Said worm is loosely mounted on longitudinal shaft 26 and is provided with suitable thrust collars 25^a, 25^b, bearing between upright supports 25^b, 25^b, as shown in

Figure 11. This worm is driven through a clutch member 27 such as a cone clutch having one element thereof keyed to the shaft 26. A gear 28 and pinion 29 forms operative connection between the motor 30 and the shaft 26 to drive the latter. The motor shown is an electric motor which is reversible, so that when the clutch 27 is engaged, the gear 20 may be rotated in either direction to raise or lower the elevating mechanism as desired. The provision of the slot 21 in the link 19 permits the cutting element to be raised independently of the elevating mechanism when said element is in contact with the ground and passes over raised or 70 rolling portions of the mine floor. Under such conditions, the link 21 slides freely along the pin 22 so as to secure this result.

In the position shown in full lines in Figures 2 and 3, the elevating mechanism is 85 shown in position to permit the cutting element 10 to rest on the mine floor, with the pin 22 on the gear 20 at the outermost end of the slot 21 in the link 19. When it is desired to raise the cutting element, as for instance, to a position shown on dotted lines in Fig. 3, the gear 20 is rotated in a clockwise direction so as to move the link 19 and arm 18 forwardly, thereby rocking the gear segments 16 and 15 and arm 14 downwardly. 95 This movement causes the forward ends of the arms 11, 11 to be raised as shown. The cutting element may thus be raised from the ground to be swung laterally into any desired position, as for instance, when it is desired to swing the cutter arm over the mine tracks.

The forward ends of the supporting arms 11, 11 are shown split and clamped on the ends 36, 36 of the rod 34 on the cutting element. The ends 36, 36 are eccentric with the body portion 35 of the rod 34, said body portion having bearing in a pair of bearing members 38, 38, carried upon a transverse bracket 37. The cutting element is provided with a cutter arm 9, and this eccentric construction of the rod 34 is for the purpose of adjusting the cutter arm by raising or lowering its outer end so that its longitudinal axis may be made parallel with the floor in the various positions of the cutting element. When, for example, the arms 11, 11, are raised or lowered, this movement tends to move the cutter arm so that it will not be longitudinally parallel with the floor, and it may then be made parallel with the floor by loosening and rotating the shaft 34 in the ends of arms, 11, 11, the eccentricity of the main body 35 and the ends 36, 36 being such as to secure this result. The cutter bar may also be tilted on its longitudinal axis by means of the pivotal connection of the bracket 37 which is mounted on a longitudinally extending pin 40 supported on the casing 41 of the cutting element 10. The 110

ends of the bracket 37 may be adjusted by means of screws 44, 44, on opposite ends of said bracket. It will thus be seen that the cutter arm may be adjusted so that it will be longitudinally parallel with the floor along which the cut is made.

The cutter of the cutting element may be of any suitable form and is herein shown as a chain 49 (see Fig. 1) mounted in the usual manner on the cutter arms 9. This cutter chain is driven in the following manner: A cutter chain sprocket 50 is mounted on an upright shaft 51 journaled in a vertically disposed stud 52. This stud is in turn journaled in the casing 41 of the cutting element 10, and is integral with a laterally projecting member 53 to which the cutter bar 9 is secured by suitable means such as bolts 54, 54. This construction is best shown in Figure 6. A bevel gear 55 is mounted at the upper end of the shaft 51 and is meshed with a horizontally disposed bevel pinion 56 on the shaft 57 which extends rearwardly through the casing 41 of the cutting element 10. An operative connection between the shaft 57 and shaft 62 mounted on a bearing 63 at the forward end of the moving frame 3, is afforded by a pair of suitable flexible connecting couplings 60, 60 of any ordinary form and a connecting shaft 51. The flexible couplings 60, 60 afford a driving connection between the actuating mechanism on the moving frame 3 and the cutter chain in all permissible positions of the cutting element. The shaft 62 is driven by gear 64 which is meshed with a gear 65 loosely mounted on shaft 26. (See Figs. 11 and 13.) A clutch on the gear 65 is adapted to be operatively connected to said shaft by a sliding clutch member 66. The shaft 26 is operatively connected to the motor 30 as hereinbefore described by gear 28 and pinion 29. The cutter chain 40 may thus be connected or disconnected at will by means of the sliding clutch 66.

The cutting element is fed laterally to the coal by means of a cable 70 on a drum 71 (see Figs. 1, 2, 6 and 15 to 19). This cable is fastened to a suitable jack or anchor, arranged in various positions desired, as shown in Figures 13 to 17. In the present instance, the drum 77 is rotatably mounted about the stud 52 and is actuated by the following mechanism: A gear 72 keyed on the shaft 26 is meshed with a gear 73 loosely mounted on shaft 74 which is concentric with the shaft 62. A gear pinion 75 is mounted to rotate with gear 73 and is meshed with a gear 76 loosely mounted on shaft 77. (See Figs. 11, 13 and 14.) The gear 76 is keyed on a hub 78 on which is carried a sun gear 79 forming a part of the planetary transmission device 80. This planetary device may be of any ordinary form and has driven member 81 keyed to a sleeve 82 which in

turn is keyed to the shaft 77. This sleeve is associated with one member of a slip clutch, as will hereinafter be more fully described. A miter gear 90 is carried on the forward end of the shaft 77 and is engaged with a miter gear 91 on a transverse shaft 92. A chain sprocket 93 is keyed on the shaft 92 and is connected by a chain 94 to a chain sprocket 95 mounted on one side of the casing 41 of the cutting element 10 (see Fig. 1). A bevel gear 96 is mounted to rotate with the sprocket 95 and is meshed with a bevel gear 97 rotatably mounted on the drum 71. The bevel gear 97 is operatively connected to the drum 71 by means of a ratchet device of any ordinary form, such as a pawl 98 adapted to engage in one or more notches 99, 99 spaced about the upper barrel of the drum (see Fig. 9). By means of the operating connections just described, the cable 70 may be wound upon the drum at a reduced speed suitable for feeding the cutter chain to the coal. When it is desired to wind the cable on the drum by hand, the pawl 98 is released and the drum 71 is then free to be rotated by any suitable means, such as a bar inserted in apertures 100, 100 formed at intervals about the lower periphery of said drum. The cable 70 is trained about suitable sets of sheaves 110, 111, 112, mounted on opposite sides of the projecting arm 53 so that the cable may be extended from the cutting element in either direction as desired.

The moving frame 3 is swung laterally by the following mechanism: The main frame 1 is provided at the rear end thereof with a rack 121. (See Figs. 1, 2 and 4.) This rack is engaged by a pinion 122 mounted on the underside of the moving frame 3. This pinion is preferably driven from the motor. Said pinion 122 is meshed with an idler pinion 123 which in turn is meshed with a pinion 124 on shaft 125. A bevel pinion 126 is mounted on the upper end of said shaft and is meshed with a bevel pinion 127 loosely mounted on a longitudinal shaft 128 as best shown in Figure 12.

In the construction illustrated in Figures 1, 12, 13 and 14, it will be seen that the bevel pinion 127 may be driven either at high or low speed, as desired. The low speed connection is as follows: A gear 129 is keyed on shaft 128 and may have driving engagement with the pinion 127 through a sliding clutch 133 feathered on said shaft. Gear 129 is meshed with gear 130 loosely mounted on shaft 132. Gear 130 is adapted to have driving engagement with said shaft through a clutch member 134 feathered on the latter. A slip clutch member 131 is keyed on shaft 132 and is mounted to rotate with a casing 84, forming one member of the slip clutch, as shown. The other member, 82^a of this clutch comprises a friction plate integral

with the sleeve 82. The members are held in frictional engagement by a plurality of springs 85, 85. The tension of the springs may be regulated by a lock nut 83, threaded on the end of sleeve 82. The slip clutch is driven through the planetary gear mechanism 80, reducing gears 75 and 76, gear 73 and the driving mechanism connected with the motor 30, as hereinbefore described. It will thus be seen that the moving frame 3 may be rotated at relatively slow speed by gearing which may now be traced as follows: gear 73 through gears 75 and 76, planetary device 80, slip clutch members 81, 82 and 131, shaft 132, clutch member 134, gears 130 and 129, shaft 128, clutch 133, bevel gears 127 and 126 shaft 125 and pinions 124, 123, 122 to rack 121.

When rotating frame 3 in this manner, the pawl 98 (see Figures 6 and 9) is preferably thrown out of engagement so that drum 71 will not be driven.

Power connections are also provided for rotating the moving frame at high speed which connections are as follows: A sliding gear 135 is mounted on the longitudinal shaft 74 as shown in Figure 13. The gear 135 is shifted laterally by means of a suitable clutch collar 161, and is provided with a clutch member 136 adapted to be moved into engagement with clutch member 137 carried by a bevel pinion 138 loosely mounted on the shaft 74. The gear 135 is meshed with gear 139 loosely mounted on shaft 132. The gear 139 is in turn meshed with gear 160 keyed on the shaft 128. The shaft 74 is driven through clutch 74^a and gear 73. It will, therefore, be noted that shafts 74 and 132 are both driven from this last named gear 73, but the shaft 74 will be driven at a relatively greater speed owing to its direct connection with this gear. The high speed connection may now be traced as follows: from shaft 74 through clutch 137, gears 135, 139 and 160, clutch 133, bevel pinions 126 and 127, shaft 125 and pinions 124, 123, and 122 to rack 121.

The power connections just described for swinging the moving frame 3 are primarily for the purpose of positioning the moving frame 3 and the cutting element 10 preparatory to the cutting operation. During the cutting operation the cutting element is preferably moved by the draft rope 70 as indicated in the diagrams shown in Figures 15 to 17. Therefore, during the cutting operation, clutch 133 is disengaged and the frame swinging mechanism is in operation. Under some conditions, however, it may be desirable to feed the cutting element to the coal by means of the power connections for swinging the moving frame 3, as for instance, the low speed connections may be used for this purpose.

The operation of the gearing mechanism

just described also provides high and low speed connections for propelling the machine bodily along the mine track. One pair of wheels 2, 2, are mounted on a shaft 176 and have driving connections with stud shaft 171 through gears 177 and 178. The other pair of wheels 2, 2, are mounted on shaft 179 and have driving connections with stub shaft 172 by a chain 180 and chain sprockets 181, 182. Stub shafts 171 and 172 are mounted on the main frame and are driven through miter gears 173, 174 which mesh with miter gear 175 on the shaft 170. A bevel gear 183 is mounted on shaft 170 which extends concentrically through the hub 4 on which the moving frame 3 swings, so as to permit the wheels to be driven in all positions of the swinging frame 3 as is best shown in Figure 5.

The bevel speed connection to bevel driving gear 183 is provided through gears 73, 75 76, planetary gear 80, slip clutch members 81, 82 and 131, shaft 132, sliding clutch 134, gears 139 and 135, clutch members 136 and 137, and bevel pinion 138.

The bevel driving gear 183 is driven at high speed through gear 73, clutch 74^a, shaft 74 and pinion 138.

In order to control the angular position of the cutting element with respect to the moving frame 3 as the latter is rotated on its axis, a pair of controlling arms 140, 140, are pivotally connected on opposite sides of an annular ring 141, loosely mounted on stud 52 of the cutting element 10. The cutter arm 9 is adapted to be locked with respect to the ring 141 by suitable means such as a locking pin 53^a projecting through the member 53 and adapted to fit in one of a plurality of holes 53^b depending upon the position of the cutter arm. It will thus be seen that the locking pin 53—A may be removed and the cutter arm swung around in any desired angle on either side of the straight forward position. The parts are arranged so the cutter arm can be moved through an angle of approximately 180 degrees. The controlling arms 140, 140, are each hinged intermediate their ends on pivots 142, 142 and extend rearwardly between the moving frame 3 and main frame 1, where they are pivotally connected on pins 144, 144, mounted on opposite sides of an anchor plate 145. This anchor plate is mounted to rotate about an annular flange 145^a extending upwardly from the main frame 1 and is best shown in Figures 4 and 5. The anchor plate may be fixed with respect to the main frame 1 by any suitable means, as for instance, a locking pin 146 may be fitted in an aperture 147 as in said plate and a registering aperture 148 in the main frame 1. In the form illustrated, these apertures are accessible through an opening 149 formed in the moving frame 3, when the latter is in the position as shown

in Figure 1. When the anchor plate 145 is fixed with respect to the main frame 1, the movement of the cutter arm is controlled as illustrated in Figures 15 and 16 in which the machine is shown as working in a narrow entry. On Figure 15, it will be seen that the moving frame 3 is swung to the right with respect to the main frame 1. Owing to the position of pins 144, 144, which are held rigidly on opposite sides of the longitudinal axis of the main frame 1, and the divergence of the controlling arms, the cutter bar 9 is swung into a slightly deflected position at a small angle to the right rib or wall of the entry. The cutter arm is thus held in a desirable position for making its sumping cut along the right rib when the machine is moved forwardly as shown. This controlling action of the arms 140, 140 is in effect a modified pantograph movement similar to that disclosed in my prior application bearing Serial No. 444,767, filed February 14, 1921, hereinbefore referred to, in which the cutter arm is inclined outwardly when it is on opposite sides of the straight forward position of the cutting element but in the latter position is in longitudinal alignment with the main frame 1. In Figure 16 the position of the cutter arm is shown at the end of the cut, that is to say, after the cutter arm has been swung laterally across the face. In this position it will be seen that the cutter arm is inclined outwardly to the left and away from the longitudinal axis of the main frame in position to be easily withdrawn when the machine is moved outwardly on the mine track. When it is desired to swing the moving frame 3 and the cutter arm 9 about a common axis, the anchor plate is released from its rigid connection with the main frame 1, and is locked with respect to the moving frame 3 by means of a locking pin 150 which is inserted through an aperture 151 in the moving frame 3 into locking engagement with an aperture 152 in the anchor plate 145. When the anchor plate 145 is thus locked to the moving frame 3, the controlling arms 140, 140 are maintained rigidly with respect to said moving frame so that no pantograph movement similar to that illustrated in Figures 15 and 16 occurs, but the controlling arms swing angularly with the moving frame. The cutter arm 9 is locked as before in position with respect to the ring 141 and the controlling arms 140, 140. The machine is then sumped with the cutter bar 9 in longitudinal alignment with the movement frame 3, and thereafter swung about a common axis with said frame 3 to cut a kerf as indicated in dotted lines in Figure 19.

The machine may also be used for making a slabbing cut, that is to say, the cutter arm 9 may be locked in position to extend laterally

from the machine and the entire machine moved bodily along the mine track as shown in Figure 17. In this position of the cutter arm, the anchor plate may be fixed with relation to the main frame 1 as shown in this figure, or it may be fixed rigidly with relation to the moving frame 3, as desired. 70

When the machine is being transported from place to place, the moving frame 3 may be rigidly locked with respect to the main frame 1 by utilizing both locking pins 146 and 150 in the anchor frame, thereby securing all the parts against lateral movement on the main frame. 75

I claim as my invention:

1. In a mining machine, a base frame, a moving frame, a swinging cutting element forward of said moving frame including a cutter arm and a support therefor, two separated arms pivotally connected at their forward ends with said cutter arm support and so connected at their rear ends to both the base and swinging frames as to be movable horizontally with respect to either, and means affording a fixed connection for the rear ends of said arms either with respect to said base frame or said moving frame. 80 85 90

2. In a mining machine, a base frame, a moving frame, a swinging cutting element forward of said moving frame, including a cutter arm and a support therefore, two separated arms pivotally connected at their forward ends with said cutter arm support and connecting means for the rear ends of said arms adjustable angularly with respect to said base frame. 95 100

3. In a mining machine, a base frame, a moving frame pivotally connected with said base frame, a swinging cutting element forward of said moving frame, including a cutter arm and a support therefor, two separated arms pivotally connected at their forward ends with said cutter arm support, connecting means for the rear ends of said arms rotatably mounted concentric with the axis of said moving frame, and means for locking said connecting means either with respect to said base frame or said moving frame. 105 110 115

4. In a mining machine, a base frame, a moving frame pivotally connected thereto on a vertical axis, a swinging cutting element forward of said moving frame, including a cutter arm and a support therefor, two separated arms pivotally connected at their forward ends with said cutter arm support and so connected at their rear ends to both the base and moving frames as to be movable with respect to either, means affording a fixed connection for the rear ends of said arms either with respect to said base frame or said moving frame, and supporting means carried by said moving frame independent of said arms for lifting and lowering said cutting element. 120 125 130

5. In a mining machine, a base frame, a moving frame pivotally connected thereto on a vertical axis, a swinging cutting element forward of said moving frame, including a cutter arm and a support therefor, two separated arms pivotally connected at their forward ends with said cutter arm support and so connected at their rear ends to both the base and moving frames as to be movable with respect to either, means 10 affording a fixed connection for the rear ends of said arms either with respect to said base frame or said moving frame, supporting means carried by said moving frame independent of said arms for lifting and lowering said cutting element, and power devices for positioning said moving frame angularly respective to said base frame.

6. In a mining machine, a base frame, a movable frame pivotally connected thereto on a vertical axis, a swinging cutting element forward of said moving frame, including a cutter arm and a support therefor, two separated arms pivotally connected at their forward ends with said cutter arm support and so connected at their rear ends to both the base and moving frames as to be movable with respect to either, means affording a fixed connection for the rear ends of said arms either with respect to said base frame or said moving frame, supporting means carried by said moving frame independent of said arms for lifting and lowering said cutting element, power devices for positioning said moving frame angularly respective to said base frame, and other power devices including flexible draft means adapted to coat with said cutting element to feed the cutter to the coal.

7. In a mining machine, a base frame, a moving frame pivotally connected with said base frame, a swinging cutting element forward of said moving frame including a cutter arm and a support therefor, two separated arms pivotally connected at their forward ends with said cutter arm support and so connected at their rear ends to both the base and moving frames as to be movable with respect to either, connecting means for the rear ends of said arms rotatably mounted concentric with the axis of said moving frame, means locking said connecting means either with respect to said base frame or said moving frame, and supporting means carried by said moving frame independent of said arms for lifting and lowering said cutting element.

8. In a mining machine, a base frame, a moving frame, a swinging cutting element forward of said moving frame, two separated arms pivotally connected at their forward ends with said cutting element, connecting means for the rear ends of said arms rotatably mounted concentric with the axis of said moving frame, means locking said

connecting means either with respect to said base frame or said moving frame, supporting means carried by said moving frame independent of said arms for lifting and lowering said cutting element and power devices for positioning said moving frame angularly respective to said base frame.

9. In a mining machine, a base frame, a moving frame, a swinging cutting element forward of said moving frame, two separated arms pivotally connected at their forward ends with said cutting element, connecting means for the rear ends of said arms rotatably mounted concentric with the axis of said moving frame, means locking said connecting means either with respect to said base frame or said moving frame, supporting means carried by said moving frame independent of said arms for lifting and lowering said cutting element, power devices for positioning said moving frame angularly respective to said base frame, and other power devices including flexible draft means adapted to coat with said cutting element to feed the latter to the coal.

10. In a mining machine, a base frame, a moving frame pivotally connected thereto on a vertical axis, a swinging cutting element forward of said moving frame, two separated arms pivotally connected at their forward ends with said cutting element and so connected at their rear ends to both the base and moving frames as to be movable with respect to either, said arms being more widely separated at their forward than at their rear ends, and means affording a fixed connection for the rear ends of said arms either with respect to said base frame or said moving frame.

11. In a mining machine, a base frame, a moving frame, a swinging cutting element forward of said moving frame, two separated arms pivotally connected at their forward ends with said cutting element, said arms being more widely separated at their forward than at their rear ends, connecting means for the rear ends of said arms rotatably mounted concentric with the axis of said moving frame and means locking said connecting means either with respect to said base frame or said moving frame.

Signed at Chicago, in the county of Cook and State of Illinois, this 27th day of October, 1922.

CHARLES E. DAVIS.
